by O. Dratte, Atty.

UNITED STATES PATENT OFFICE.

HENRY M. CROWELL, OF IRVINGTON, ASSIGNOR OF ONE-HALF TO GEORGE T. CARTER, OF ELIZABETH, NEW JERSEY.

EXTENSIBLE MOSQUITO-BAR FRAME.

SPECIFICATION forming part of Letters Patent No. 269,390, dated December 19, 1882.

Application filed October 9, 1882. (No model.)

To all whom it may concern:

Be it known that I, HENRY M. CROWELL, a citizen of the United States, residing at Irvington, in the county of Essex and State of New Jersey, have invented certain new and useful Improvements in Extensible Mosquito-Bar Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to facilitate the adjustment of the frame to windows of different sizes, to strengthen the frame, to render it more durable, and to reduce the cost of construction.

20 The invention consists in the peculiar construction, combination, and arrangement of the several parts by means of which the frame is capable of being adjusted both vertically and horizontally, as will be set forth herein-
25 after.

In the drawings, Figure 1 is a front elevation of my improved device. Fig. 2 is a section (enlarged) taken through line *x*, and Fig. 3 illustrates a modified form of the device.

30 In carrying out my invention I construct four hollow and slotted angle irons or boxes, *b*, which form the four corners of the frame, of sheet metal, in which are adjusted strips or bars of wood *a a'*, arranged to operate in connection with said irons as follows—to wit, the strips *a a'* are placed in pairs within the boxes, as shown. In each pair one of the strips, *a*, is firmly secured by screws, rivets, or otherwise to one of the angle-irons at one end and allowed 40 to slide in the socket of the opposite iron, while the other strip, *a'*, is secured in the last said iron and slides in the first. By this construction and arrangement the size of the frame may be increased or diminished in both vertical and horizontal directions by simply pulling the frame apart or pressing it together, as

the strips of wood slide freely in the operation, as will be readily understood. Ample room is afforded by means of the slot to fasten the netting or wire-cloth to the wood, which, being 50 done, serves to hold the parts of the frame in fixed relation to one another after said frame has been adjusted to a given size.

If it be desired to reduce the size of the frame, the netting must be loosened, the parts 55 pressed together, and the netting cut off to suit.

Brackets or braces *c* may be employed to give added strength to the frame. The slot *g* in the angle-irons may be in the side of the iron, 60 as shown in Fig. 2, or within the inner face thereof, as shown in Fig. 3. The netting may be tacked directly to the frame, or a cleat, *e*, be employed, as shown in Fig. 3, the latter method being preferable, as the cleat fitting in the 65 slot gives a superior finish to the frame, as well as giving greater security to the said netting and holding the part into a more rigid or fixed relation.

Having thus described my invention, what I 70 claim as new, and desire to have secured by Letters Patent, is—

1. The combination, with the hollow angle-irons, of the bars *a a'*, arranged therein, substantially as and for the purposes set forth and shown. 75

2. As an improved article of manufacture, an adjustable mosquito-bar frame consisting of the four hollow and slotted angle-plates *b* and the strips of wood arranged therein in 80 pairs, one of each pair being secured to the outer portion of each side and the other to the inner portion, substantially as shown and described.

In testimony that I claim the foregoing I have 85 hereunto set my hand this 25th day of September, 1882.

HENRY M. CROWELL.

Witnesses:

OLIVER DRAKE,
GEORGE T. CARTER.
